SHUTTLE CHECKING MECHANISM

Albert A. Gordon, Worcester, Mass., assignor to
Crompton & Knowles Loom Works, Worcester,
Mass., a Corporation of Massachusetts

Application December 30, 1931
Serial No. 583,932

9 Claims. (Cl. 139—187)

This invention relates to mechanism for checking the flight of a shuttle in a fly shuttle loom.

It is the object of my invention to provide a mechanism effective to stop the shuttle in a predetermined position in the shuttle box, and preferably without engagement of the picker.

A further object of the invention is to provide means by which increased pressure may be applied to the shuttle as it closely approaches final boxed position, together with means by which such increased pressure will be relieved before the shuttle is picked from the shuttle box.

My invention further relates to arrangements and combinations of parts which will be hereinafter described and more particularly pointed out in the appended claims.

A preferred form of the invention is shown in the drawings, in which

Fig. 1 is an end elevation of a loom having my invention applied thereto;

Fig. 2 is an enlarged front elevation of the lay end and parts associated therewith;

Fig. 3 is a detail plan view, looking in the direction of the arrow 3 in Fig. 2;

Fig. 4 is a detail front elevation, looking in the direction of the arrow 4 in Fig. 1, and

Fig. 5 is a detail sectional plan view, taken along the line 5—5 in Fig. 1.

Referring to the drawings, I have shown certain parts of a drop box loom including a loom side 10 and a lay 11, supported on the usual swords 12 and swinging on a rock shaft 13. A lay end 15 is mounted on the end of the lay 11 and is provided with guideways for a set of shifting shuttle boxes 17, one such guideway being shown at 18 in Fig. 3. The shuttle boxes are mounted on a lifter rod 19 and are shifted vertically by pattern-controlled mechanism of the usual type.

Each shuttle box is provided with a binder 20, pivoted at 21 near the left hand end of the drop boxes 17 as viewed in Fig. 2. Binder springs 22 are provided for the binders 20, said springs being secured by screws 23 (Fig. 3) to the front of the drop boxes 17.

A picker P is slideable lengthwise of the lay on a guide-rod 25 and is mounted to engage the shuttle S which is actively positioned opposite the picker. A picker stick is provided for actuating the picker P.

The parts thus far described are of the usual construction and in themselves form no part of my present invention, which relates particularly

to the provision of a checking member 30, movable as will be described into the path of the in-coming active shuttle S.

The checking member 30 is loosely pivoted at 31 on a projection 32 of a positioning arm 33, the upper end of which is pivoted at 34 on a bracket 35 extending outward from the lay end 15. The lower end of the arm 33 is connected by a link 37 to a bell crank 38 which is pivoted at 39 on a bracket 40 secured to the under side 65 of the lay 11.

A link 42 is connected at its upper end through a swivel member 43 to the horizontal arm of the bell crank 38 and is connected at its lower end to the front end of a cam lever 44, pivoted on 70 a bracket 45 secured to the loom side 10.

A cam roll 46 at the rear end of the lever 44 is engaged by a cam 48 mounted on the bottom or cam shaft 50 of the loom, said shaft making one revolution to each two beats of the lay. The cam 48 has raised portions 51 and depressed portions 52, both preferably concentric with the shaft 50. A spring 53 acts to hold the cam roll 46 against the surface of the cam 48.

A relatively heavy spring 54 (Fig. 2) is interposed between a collar 55, adjustable on the link 37, and a bracket or guide 56 mounted on the lay end 15. A stop screw 57 is threaded and adjustable in the arm 33 and engages the outer face of the lay end 15, thus limiting the swinging movement of the arm under the influence of the spring 54.

A flat spring 60 (Figs. 2 and 3) engages the inner face of the member 30 and yieldingly resists swinging movement thereof into the path of the shuttle. The free end of the member 30 is shaped to fit the tapered end of the shuttle S, and is preferably provided with a covering 62 of leather or other suitable friction material.

Each binder 20 is extended outward beyond the pivot 21, as indicated at 64, and the outward extension 64 of the binder 20 associated with the active shuttle is engaged by the front face of the member 30, as indicated in Fig. 3.

The extreme front end surface of the member 30 is beveled, as indicated at 65, to promote movement of the parts to operative position and also to quicken the release of pressure, as will be hereinafter described.

After the shuttle has been picked and the boxes have been shifted, the roll 46 drops into a depressed portion 52 of the cam 48 and the springs 53 and 54 cooperate to move the checking member 30 to the operative position indicated in Fig. 3, in which position the spring 60

maintains the member 30 in yielding contact with the projection 64 of the binder 20.

As the shuttle S approaches final boxed position, the tapered end of the shuttle engages the 5 inclined inner end of the member 30, attempting to force the member 30 outward. Such attempted outward movement causes the member 30 to press firmly against the projection 64, thus causing the binder 20 to more firmly engage 10 the shuttle S and to effectively prevent rebound thereof. At the same time, the inclined face of the member 30 prevents movement of the shuttle beyond a predetermined point, which point is preferably such that the shuttle does 15 not engage the picker 3, as indicated in Fig. 3.

As soon as the shuttle is thus brought to rest, a raised portion 51 of the cam 48 engages the roll 46 and positively withdraws the member 30 out of engagement with the shuttle S and also 20 out of engagement with the projection 64 of the binder 20. The member 30 is thus freed from the drop boxes and from all parts associated therewith and the boxes may thereafter be freely shifted as usual, and the shuttle may be 25 picked under reduced binder pressure.

Should the member 30 remain in partial contact with the shuttle S or with the projection 64, guides 70 (Fig. 2) on the lay end 15 will prevent any substantial vertical movement of the 30 member 30.

Having thus described my invention and the advantages thereof, I do not wish to be limited to the details herein disclosed, otherwise than as set forth in the claims, but what I claim is:—

35. 1. In a loom having a lay, a shuttle, a shuttle box and a binder, in combination, a checking member mounted for movement longitudinally of the shuttle box toward the incoming shuttle and effective in advanced position to apply increased force to the binder as the shuttle reaches final boxed position, and means to advance said member before the shuttle is boxed.

40. 2. In a loom having a lay, a shuttle, a picker, a shuttle box and a binder, in combination, a checking member additional to said picker and mounted for movement longitudinally of the shuttle box toward the incoming shuttle, means to move said member to operative position just prior to each boxing of the shuttle, and means to withdraw said member after each boxing of the shuttle.

45. 3. In a loom having a lay, a shuttle, a picker, a shuttle box and a binder, in combination, a checking member additional to said picker and mounted for movement longitudinally of the shuttle box toward the incoming shuttle, yielding means to move said member to operative position just prior to each boxing of the shuttle, and positive means to withdraw said member after each boxing of the shuttle.

4. In a loom having a lay, a shuttle, a shuttle box and a binder, in combination, a checking member mounted for movement longitudinally of the shuttle box toward the incoming shuttle, means to move said member to operative position just prior to the boxing of the shuttle, and means to withdraw said member after the shuttle is boxed; said member when in advanced position engaging the binder and being effective to apply increased force to the binder as the shuttle is boxed.

5. In a loom having a lay, a shuttle, a picker, a shuttle box and a binder, in combination, a checking member additional to said picker and mounted for movement longitudinally of the shuttle box toward the incoming shuttle, means to move said member to operative position just prior to each boxing of the shuttle, and means to withdraw said member after each boxing of the shuttle; said binder having a portion projecting beyond its pivot and engaged by said member as the shuttle presses said member outward.

6. In a drop box loom having a picker, shifting shuttle boxes, a plurality of shuttles and a shuttle binder for each box, in combination, a checking member additional to said picker and mounted in permanent alignment with the active shuttle box and movable longitudinally of the shuttle box toward an incoming shuttle, and means to move said member forward to operative position, said member when in forward operative position engaging an outwardly projecting portion of said binder.

7. In a drop box loom having a picker, shifting shuttle boxes, a plurality of shuttles and a shuttle binder for each box, in combination, a checking member additional to said picker and mounted in alignment with the active shuttle box and movable longitudinally of the shuttle box toward an incoming shuttle, and means to move said member forward to operative position, said member having an inclined shuttle engaging face by which said member is forced sideways, thereby more firmly engaging a portion of a binder and applying increased binder pressure as the shuttle reaches boxed position.

8. The combination in a loom as set forth in claim 7, in which positive means is provided for withdrawing said checking member and for thereby releasing the increased binder pressure after each shuttle is boxed.

9. The combination in a loom as set forth in claim 7, in which a continuously rotated cam permits yielding advance of said checking member prior to each boxing of a shuttle and effects periodical and positive withdrawal thereof after each boxing thereof of a shuttle.

ALBERT A. GORDON. 135
